UNITED STATES PATENT OFFICE.

EDWARD VOLTERS, OF ST. LOUIS, MISSOURI.

FOLDABLE BATH-TUB.

1,307,942.

Specification of Letters Patent. Patented June 24, 1919.

Application filed July 31, 1918. Serial No. 247,621.

To all whom it may concern:

Be it known that I, EDWARD VOLTERS, a citizen of the United States, residing at St. Louis, in the county of St. Louis City 5 and State of Missouri, have invented certain new and useful Improvements in Foldable Bath-Tubs, of which the following is a specification.

This invention relates to folding bath 10 tubs, and more particularly to those having collapsible frames.

The object of the invention is to provide an inexpensive bathing apparatus adapted for use in bed rooms without bath fixtures 15 or in camps where it will be useful for engineers, soldiers, surveyors, miners and others.

Another object is to so construct a tub of 20 this character which when collapsed will occupy a minimum amount of space and be comparatively light for transportation and when opened up will be strong and efficient for use.

With the foregoing and other objects in view, which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings:—

Figure 1 represents a perspective view of 35 a bath tub constructed in accordance with this invention, set up ready for use,

Fig. 2 shows a perspective view of the collapsed frame of the tub in collapsed position,

Fig. 3 is a perspective view of the water 40 receptacle in the position which it assumes when connected to the frame, the ends being shown slightly open, and

Fig. 4 is a side elevation of the frame in 45 partially set up position.

In the embodiment illustrated, the collapsible form of the tub constituting this invention comprises two side bars 1, and end bars 2 connected at the corners by L-shaped connectors 3. Each side bar 1 is composed of two sections 4 and 5 pivotally connected at their inner ends and at their outer ends offset outward and pivoted to one arm by the connector 3, the other arm of 50 said connector being pivotally connected with one end of the end bars 2. These end

bars 2 are also composed of two sections 6 and 7 pivotally connected at their inner ends, one of said sections having a laterally extending lug 8^a on its lower edge which projects beyond the pivotal connection with 60 the adjacent sections and forms a stop or rest for the sections when in open operative position to prevent collapse of the frame. This collapsible frame, the end and side 65 members of which are of a lazy tong construction has its side bars supported by pivotally connected links or bars 8 and 9, two pairs of which are here shown intersecting each other midway their ends and pivotally 70 connected as shown at 10. The inner ends of the bars 9 of each pair are pivotally connected as shown at 11, while the inner ends of bars 8 are pivotally connected as shown at 12 and one of said bars has a laterally 75 extending finger 13 which is adapted to project over the pivotal connection of the sections 4 and 5 of each of the side bars 1 to limit the upward movement of said side bars and to prevent downward movement of 80 the connected bars 8 when in operative position. These lugs 13 are apertured as shown at 14 to receive ties or leashes 15 which are designed to connect the side bars with the toggle joint structure of the side frames and 85 also a water containing receptacle herein-after to be described.

The upper ends of the bars 9 are pivotally connected to the angle bars or L-shaped members 3 between said members and the ends of 90 the sections 4 and 5 of the side bars as is shown clearly in Fig. 4. The lower ends of the bars 8 are pivotally connected with L-shaped connectors 16 similar in construction to those 3 which are used at the upper corners of the frame. These L-shaped connectors 16 are also pivotally connected with the lower ends of a pair of crossbars 17 and 18 which are arranged at the ends of the tub as 95 is shown clearly in Fig. 1. These bars 17 and 18 intersect each other midway their length and are pivotally connected as shown at 19, while their upper ends are pivoted to the connectors 3 between said connectors and the end sections 6 and 7 of the end members 2.

From the above description it will be obvious that by bending the sections 4 downwardly at their pivotally connected ends and similarly bending the end sections 6 and 7, 110 the frame which is of a toggle joint lazy tong structure will fold upwardly into a very

small space as shown in Fig. 2 and if desired it may be used when folded to surround and retain the water receptacle now to be described, although it need not necessarily 5 be used in this connection.

The body of the tub or the water receptacle consists of a rectangular sheet 20 of any suitable waterproof fabric, the edges of said sheet being reinforced as shown at 21 and 10 provided with circular metal eyelets 22 which are so arranged that when cords or ties 23 are placed therein the sheet will be folded into the position shown in Figs. 1 and 3, and when these ties 23 are threaded through the eyelets and passed around the frame with the 15 bottom thereof resting on the supporting surface, and may be used in the ordinary manner of a bath tub.

When not in use or desired for transportation, the water container is detached from the frame by loosening the ties 23 and it may be rolled up into a small space and the frame collapsed either around the container or not, so that it may be packed in a small space for 25 transportation or storage and when desired may be readily set up for use with a minimum amount of labor.

The frame which constitutes a part of this invention may be composed of any suitable 30 metal preferably of aluminum to render it as light as possible and yet strong.

Owing to the fact that the bottom of the tub rests on the floor when in use, there will be very little strain upon the frame so that 35 the strips or bars from which it is constructed may be quite light and yet support the tub in operative position.

The foregoing description and the drawings have reference to what may be considered the preferred or approved form of my 40 invention. It is to be understood that I may make such changes in construction and arrangement and combination of parts, materials, dimensions, etc., as may prove expedient and fall within the scope of the claimed 45 invention.

Having thus fully described my invention, what I claim as new and desire to secure by Letters Patent, is:—

50 1. A collapsible bath tub comprising a

frame composed of two sets of L-shaped corner members for the upper and lower corners of the tub, sectional end and side bars pivoted to the arms of the upper corner members, lazy tong structures forming side 55 and end members and connecting the upper and lower corner members, means for holding said structures in open operative position, and a foldable flexible container supported by said frame.

2. A collapsible bath tub comprising a frame composed of two sets of L-shaped corner members for the upper and lower corners of the tub, sectional side and end bars pivoted to the arms of the upper corner members, lazy tong structures forming side and end members connecting the upper and lower corner members, the side members having laterally extending fingers at their 60 upper ends, the sections of the side bars being pivotally connected and engaged at their pivotal connection by said fingers whereby the frame is held in extended operative position, and a foldable flexible container supported by said side bars.

3. A collapsible bath tub comprising a frame composed of two sets of L-shaped corner members for the upper and lower corners of the tub, sectional side and end bars pivoted to the arms of the upper corner members, lazy tong structures forming side and end members connecting the upper and lower corner members, the side members having laterally extending fingers at their 65 upper ends, the sections of the side bars being pivotally connected and engaged at their pivotal connection by said fingers whereby the frame is held in extended operative position, and ties extending around said side and end members, and a flexible container also 70 engaged by said ties whereby the frame and the container are held in open operative position.

In testimony whereof I affix my signature in presence of two witnesses.

EDWARD VOLTERS.
